END CAP FOR CANISTER-TYPE GRENADES AND THE LIKE

Irwin R. Barr, Lutherville, and Robert W. Schnepfe, Jr.,
Timonium, Md., assignors to AAI Corporation,
Cockeysville, Md., a corporation of Maryland

Filed Dec. 20, 1965, Ser. No. 240

Term of patent 14 years

(Cl. D30—1)

FIG. 1

FIG. 2

FIG. 3

FIG. 4

FIG. 5

FIGURE 1 is an isometric view of an end cap embodying the design according to the invention.

FIGURE 2 is an isometric view of the embodiment of FIGURE 1, as viewed toward the opposite face of the embodiment.

FIGURE 3 is a plan view looking toward the end face of the embodiment as seen in FIGURE 1.

FIGURE 4 is a plan view looking toward the end face of the embodiment as seen in FIGURE 2, and

FIGURE 5 is a side elevation of the embodiment of FIGURE 1.

We claim:

The ornamental design for an end cap for canister-type grenades and the like, as shown.
